UNITED STATES PATENT OFFICE.

FREDERICK GRIMME, OF CHICAGO, ILLINOIS.

BINDER-FRAME.

No. 922,693.

Specification of Letters Patent.

Patented May 25, 1909.

Application filed June 22, 1908. Serial No. 439,742.

To all whom it may concern:

Be it known that I, FREDERICK GRIMME, a citizen of the United States, residing at Chicago, in the county of Cook and State of Illinois, have invented new and useful Improvements in Binder-Frames, of which the following is a specification.

This invention relates to loose leaf binder frames for holding ledger and other leaves, 10 circulars, catalogues, etc., and its object is to provide a frame of simple and inexpensive construction adapted to receive and hold the leaves secure and evenly and permit them to be easily inserted or removed.

15 Further objects of the invention are to provide a binder frame with a round back; to cause the stub ends of the leaves to spring up like a spring back book and the leaves to lie flat when the book is opened; and to provide simple means for adjusting the book.

20 With these and other objects in view the invention consists of certain improvements on the frame disclosed by my Letters Patent No. 796,322 dated August 1, 1905 and which 25 will be fully pointed out hereinafter in the detail description of the accompanying drawings, in which—

Figure 1 is a plan view of the binder frame. Fig. 2 is a sectional view on the line 2—2 of 30 Fig. 1. Fig. 3 is an enlarged detail sectional view. Fig. 4 is an end view showing the locking mechanism. Fig. 5 is a sectional view on the line 5—5 of Fig. 4. Fig. 6 is a detail sectional view of the rubber head.

35 In the drawings, 7 designates the back of the book which is made of resilient material in the shape of a round-back book. The covers 8 are hinged to the back in any manner familiar to book binders but preferably 40 by means of the covering 9 which may be made in one piece to cover the back and cover boards, as shown in Fig. 2.

A center plate 10 having upturned ends 10' is arranged centrally within the back and 45 a plurality of yielding spring steel connections 11 are adjusted to said center plate. Clamping plates 12 having inwardly projecting edges 12' to engage the leaves (not shown) are mounted on the ends of the yielding connections. The clamping plates are bent to 50 form a socket 13 to receive a pivot pin 13' which rests in said socket and engages hinge members 14 fastened to the covers and pro-

jecting outward from the covers through openings 15 in the clamping plates. Thus 55 the covers are hinged to the frame and the clamping plate constitutes one member or leaf of the hinge and the parts 14, which are fastened to the cover board, constitute the other member of the hinge. These hinge 60 members 14, project through the openings 15 in the clamping plates to align with the socket grooves 13 so that the pivot pins 13' may be readily inserted or removed.

Two rollers 16 of the same diameter are 65 mounted in parallel relation in the ends of the center plate and are provided with intermeshing gears 17 so that they will rotate together. One of the rollers is provided with an extension 18 to receive a key. Tapes 19 70 are fastened at their ends to the rollers and they pass over guide rollers 20 which are mounted on pins 20' arranged in socket 21 in the clamping plates.

It will be observed that the clamping plate 75 is bent to form the socket 13 on one side to receive the pivot pin 13' and also to form the socket 21 on the other side to receive the guide roller pin 20'. The spring connections 11 are extended up to overlap the pins 20' 80 (Fig. 3).

The tapes are preferably fastened to the rollers in some manner interiorly thereof to avoid providing a projection on the surface of the roller which might have a tendency to 85 make the rollers wind unevenly. I have shown one way of accomplishing this result in the drawings in which the rollers are provided with longitudinal slots 22, the ends of the tape being inserted in said slots, after 90 which the roller is clamped upon the ends of the tape by a hammer blow or pressure.

The rollers are locked in adjusted position by a locking dog 23 which engages a ratchet wheel 24 on one of the rollers. A spring 25 95 operates on the locking dog to hold it in engagement with the ratchet wheel and in the particular construction illustrated in the drawings the dog is located on one side of the end 10' of the center plate and the spring 25 100 on the other side. The dog is provided with a projection 26 which extends through a slot 27 in said plate to be engaged by the spring 25. The dog is released from engagement 105 with the ratchet wheel by a cam 28 carried by a push bar 29 which is supported in brack-

ets 30, 30' on the end 10'. This cam is normally held out of operative engagement with the dog by a spring which may be in the form of a coil spring 31 located on the push bar between the end 10' and the bracket 30' and bearing against the cam 28 (Fig. 5).

I may provide heads 32 made of rubber or other suitable material at the ends of the back 7. These heads are shown in Fig. 1 and 10 in broken lines in Fig. 2 and a detail section is shown in Fig. 6. The heads are fastened to the back of the book, at the ends thereof, in any suitable manner, and they preferably overlap the same to form the projections 33 15 on which the book may rest. These heads are divided into sections so that the back of the book may be extended or contracted as required.

Braces 34, preferably of the same material 20 as the connections 11, are fastened to the clamping plates adjacent to said connections and extend approximately to the center plate. These braces tend to push the middle part of the back down as the edges are drawn 25 together when the rollers are turned to wind the tapes thereon.

I may use a leaf made as disclosed in my Letters Patent No. 767,940 dated Aug. 16, 1904 or any other leaf which is or may be 30 adapted to this binder.

My improved binder frame is light in weight but strong and substantial in construction and comparatively inexpensive to manufacture. Each frame is capable of adjustment to hold a greater or less number of leaves and at all times the binder will hold the leaves regardless of the number evenly and properly in place. The construction is such that when the book is opened the stub 40 end will spring up like a spring back book and the leaves will lie flat and close together at the points therein without spreading and exposing the tapes in the manner set forth and described more fully in my Patent No. 45 796,322 hereinbefore referred to. When it is desired to insert or remove a leaf or leaves the locking dog is released by pushing the push bar in and then the clamping plates may be spread apart as far as desired. After 50 the leaf is inserted or removed the rollers are wound up to tighten the clamping plates on the stub of the book by applying a key to the projection 18. The hinge members 14 are made of metal in any suitable manner and 55 are located on the inner sides of the covers so that the outer side of the covers will be perfectly flat. A removable canvas cover may be used on the book and this cover will conform to the back of the book whether the back 60 is extended or contracted to receive a large number or a few leaves. I may use a removable key, as heretofore mentioned, or a permanently attached key on the projection 18.

What I claim and desire to secure by Letters Patent is:

1. A binder frame comprising a resilient round back, a pair of rollers arranged side by side lengthwise within the back, said rollers being geared together to rotate in unison, and a plurality of tapes fastened at their ends to the rollers and connected to the edges of the back to adjust said edges uniformly toward and from each other. 65 70

2. A binder frame comprising a resilient round back, guides at the edges of the back, a pair of rollers arranged side by side lengthwise within the back, said rollers being geared together to rotate in unison, and a plurality of tapes fastened at their ends to the rollers and traveling over said guides to 75 80 adjust said guides uniformly toward and from each other.

3. A binder frame comprising a resilient round back, yielding connecting strips extending transversely within the back and located at intervals between its ends, clamping plates at the ends of the strips, a plurality of tapes guided in said plates, and means within the back to adjust said tapes and move the plates uniformly toward and 85 90 from each other.

4. A binder frame comprising a round back, yielding connecting strips extending transversely of the back and located at intervals between its ends, clamping plates at the ends of said strips and at the edges of the back, a pair of rollers mounted in the back to rotate in unison, and a plurality of tapes fastened at their ends to the rollers and guided in said clamping plates to adjust 95 100 said plates uniformly toward and from each other.

5. A binder frame comprising a round back, yielding connecting strips extending transversely of the back, clamping plates at the ends of said strips and at the edges of the back, said plates having openings therein and being bent to form lengthwise sockets, pins seated in said sockets, guide rollers on 105 110 said pins at said openings, tapes guided on said rollers, and means within the back for adjusting the tapes.

6. A binder frame comprising the covers, a resilient round back, clamping plates at the edges of the back and provided with openings, said plates being bent transversely throughout their length to form lengthwise sockets, pins seated in said sockets, and hinge members fastened to the covers and engaged with said pins at said openings. 115 120

7. A binder frame comprising the covers, a resilient round back, clamping plates at the edges of the back and provided with openings, said plates being bent to form lengthwise sockets on opposite sides thereof, pins seated in said sockets, hinge members 125

fastened to the covers and engaged with one set of pins at the openings, rollers on the other set of pins at the openings, tapes guided on said rollers, and means within the back for 5 adjusting the tapes.

8. A binder frame comprising a round back, yielding connecting strips extending transversely within the back, clamping plates at the ends of the strips, braces on the strips, 10 tapes guided in the clamping plates, and means within the back to adjust said tapes.

9. A binder frame comprising a round back, yielding connecting strips extending transversely within the back, clamping plates 15 at the ends of the strips, yielding braces fastened to the clamping plates upon the strips, tapes guided in the clamping plates, and means within the back to adjust said tapes.

10. A binder frame comprising a round 20 back, a center plate within the back, clamping plates at the edges of the back, spring metal strips located at intervals between the ends of the back and fastened to the center and clamping plates, a pair of rollers mounted 25 on said center plate to rotate in unison, and a plurality of tapes fastened at their ends to said rollers and guided in said clamping plates to adjust said plates uniformly toward and from each other.

30 11. A binder frame comprising a resilient round back, clamping plates at the edges of the back, a pair of rollers mounted in the

back and geared together, tapes fastened at their ends to the rollers and guided in said clamping plates, means for locking the rollers, 35 and means for releasing said locking means.

12. A binder frame comprising a resilient round back, clamping plates at the edges of the back, a pair of rollers mounted in the 40 back and geared together, tapes fastened at their ends to the rollers and guided in said clamping plates, means for locking the rollers comprising a ratchet wheel on one roller, a spring pressed locking dog engaging said ratchet wheel, and releasing means comprising 45 a spring pressed push bar, and a cam on said push bar to engage the locking dog.

13. A binder frame comprising a round back, and a flexible head arranged in said back at the end thereof, said head being divided 50 to form a plurality of projections extending inwardly and adapted to spread apart or close together as the back is extended or contracted.

14. A binder frame comprising a round 55 back, and a head arranged at each end of the back, said head overlapping the end of the back, on the outer side thereof, and provided with a plurality of projections extending inwardly.
